UNITED STATES PATENT OFFICE.

JOHN W. COTTINGHAM, OF COLUMBUS, OHIO.

CARBURETOR.

Application filed June 26, 1925. Serial No. 39,706.

This invention relates to improvements in carburetors and has for its primary object the provision of an efficient and simple carburetor constructed to automatically deliver a correctly proportioned fuel charge to the cylinders of an internal combustion engine under all conditions of operation of said engine so that efficient operation will be obtained and at the same time high economy effected in the fuel consumed.

For a further understanding of the invention reference is to be had to the following description and to the accompanying drawings, in which:

15 Figure 1 is a vertical sectional view taken through the carburetor constructed in accordance with the features of the present invention,

Figure 2 is a top plan view thereof,

20 Figure 3 is a vertical transverse sectional view on the line 3—3 of Figure 1, and

Figure 4 is a similar view on the line 4—4 of Figure 1.

My improved carburetor consists preferably of a casing 1, which has its lower end threaded for the reception of a base fitting 2, which is formed to comprise an air inlet conduit 3 and a liquid hydro-carbon fuel inlet conduit 4. The fuel conduit includes a 25 communicating pipe 5 which leads from the automatically operating float control mechanism 6, by means of which liquid fuel is led, in the ordinary manner common to devices of this character to the nozzle 7 of the inlet 4 which is arranged axially and 30 within the lower part of the casing 1.

The vertically extending nozzle 7 of the conduit 4 includes a threaded socket in which is positioned a valve seating member 40 8, which includes an axially extending port terminating at its lower end in a valve seat 9, above which is arranged horizontally disposed radiating liquid outlet ports 10. To control the flow of the liquid fuel through the member 8 there is provided a longitudinally movable stem 11, which terminates at its lower end with a needle valve 12, arranged for cooperation with the seat 9. It will be seen that as the stem is moved longitudinally away from said seat fuel, it will be drawn from the float chamber 6, through the conduit 4, past the seat 9 and thence through the ports 10 into the mixing chamber of the carburetor for intimate commingling with the air supply.

Seated upon an annular shoulder provided

ed upon the member 8 is a crown piece 13, which includes on its lower face an internal depression whose side wall is spaced from and surrounds the ports 10. Also, the 60 crown piece 13 includes a circular and upwardly and angularly extending face 14, which is spaced from a similarly formed face 15 provided upon the nozzle 7. The member 7, immediately below the face 15 is 65 provided with air inlet ports 16, by means of which air, obtained from the conduit 3 is drawn into the nozzle 7 and commingled with the liquid fuel which issues from the ports 10 and supplies a propelling force 70 which forces the fuel between the nozzle faces 14 and 15 so that the resultant mixture will issue from the open circular rim 17 of the nozzle 7.

Within the casing 1 there is mounted a 75 piston 18, which is formed to comprise at its lower end internally disposed appropriately bulged walls 19, the latter being arranged so that the smallest diameter, as shown in Figure 1, will register with the 80 rim 17 when the piston is in its lowermost position, and as the piston rises, in responding to engine suction, the wider diameter portions of the walls 19 will be gradually brought into registration with the rim 17 so 85 as to produce a wider valve opening, allowing greater quantities of the vaporized fuel to pass into the casing 1 and thence to the engine. The extent of this valve opening is regulated automatically by the operation of the associated engine and in accordance with the fuel demands of the engine. The lower edge of the piston 18 is provided with air inlet openings 20, which permit the flow of air into the carburetor to produce a combustible mixture even when the piston has reached its lowermost position in the casing 1. It will be seen that air, responding to engine suction, will travel through the conduit 3, and thence through the openings 20, if the piston valve 18 is not elevated, and into the Venturi passage of the piston produced by the walls 19. A portion of this air supply will pass through the ports 16, drawing the liquid fuel through the ports 10 to the open annular discharge rim 17 of the fuel conduit 4. The remainder of the air supply travels along the walls 19 past the rim 17 and it also creates a suction in the fuel valve which 100 consists in the drawing of the liquid fuel between the opposed faces 14 and 15 of the 105

nozzle 7 producing a vaporized or carburetted mixture suitable for delivery to the engine cylinders. It will be seen that as the suction of the engine is increased, due to a varying load condition, the piston valve 18 will respond to the suction and will rise to a sufficient extent, regulated automatically, to admit of a greater inflow of the fuel through the carburetor, and, conversely, as the suction decreases the piston valve recedes automatically to diminish the fuel supply.

In order to produce a more intimate commingled and vaporized fuel mixture, the upper part of the piston 18 is provided with one or more stationary screens 21 which serve to break up the liquid particles of the fuel and to permit generally of their more complete vaporization. In addition to the stationary screens, the axial hub 22 of the piston has its lower end provided with one or more perforated fans 23, the blades of which being so arranged as to effect rotation on the part of the fan during gas travel through the carburetor. This fan, also, acts in conjunction with the vaporizing nozzle of the carburetor to break up the liquid particles contained in the fuel stream, so that such particles will more readily combine with the air to produce the desired gaseous mixture, as far as practicable, desired in hydro-carbon fuel carburation.

The stem 11 of the needle valve extends upwardly and axially from the member 8, through the hub 22 and is slidably received within a gland 24 carried in the top of the manifold fitting 25 of the carburetor. This fitting communicates directly with the open upper portion of the casing 1 and is provided with a flanged end 26 adapted for association with the inlet manifold structure (not shown) of an internal combustion engine. Also, the fitting is provided with the usual butterfly valve 27, operated manually in the usual manner. A spring 28 is in this instance placed around the stem 11 between the gland 24 and the upper part of the hub 22. This spring normally serves to force the piston valve downwardly and serves to stabilize the operation of the piston valve 18, permitting the latter to rise and fall in response to the internal suction of the associated engine. I prefer to use the spring 28, but it will be apparent that if desired this spring can be eliminated and the operation of the piston returned by gravity to a normal position. Tension on the spring may be adjusted by the movement of the gland 24. It will be seen that as the motor speed increases the piston 18, which is in reality an air regulating valve, rises, allowing more air to pass the fuel nozzle, reducing the strength of the mixture to correspond to the speed of the motor. When the motor is at rest, the air valve 18 descends to its lowest point. In this lowered position

the carburetor is positioned automatically for easy starting as a very rich fuel mixture is initially obtained.

Connected with the hub 22 is an upwardly extending rod 29 which projects upwardly beyond the casing through an opening 30 provided in the upper portion of the fitting 25. The upper end of the rod 29 is provided with a yoke 31 with which is pivotally connected a link 32. The upper end of the link 32 is pivotally connected as at 35 to the outer end of a bell crank lever 36 which has its intermediate portion pivoted at 37 to a bracket 38 extending from the fitting 25. The short arm 36a of the bell crank lever has its lower end provided with a roller 39 which is arranged to ride upon the edges 40 of a triangular shaped cam member 41. This member is pivoted as at 42 upon the outer end of a fulcrum arm 43 and in this instance the arm 43 has pivotally connected thereto an upright screw 44, carrying at its upper end an adjustable threaded nut 45, the spring 46 being interposed between the nut and the edge of the arm 43 so as to maintain the cam 41 in a set position of operation. The intermediate portion of the arm 43 is provided with an opening 47 in which is slidably received the upper end of the stem 11, the latter being provided with a threaded nut 48 which bears upon a fulcrum washer 49, so that the oscillations of the arm 43 would result in imparting control movement to the needle valve which is used in controlling the liquid fuel supply. The other end of the arm 43 is provided with an adjustable screw 50, which presses upon a guided bracket plate 51 and is supported by means of a sliding wedge 52, carried in connection with a fitting 25. The wedge 52 is manually operated, and it will be seen by reciprocating the same the needle valve 12 may be raised and lowered by a manual setting independently of the automatically operating features of the carburetor.

In the operation of the carburetor it will be seen that when an associated engine is first started a comparatively rich mixture will be imparted to the cylinders thereof by the present carburetor. This is due to the fact that when the engine is first started the suction created within the mixing chamber and the carburetor is comparatively small, allowing the piston valve to close substantially the air inlet conduit, except for the small amount of air which passes through the restricted openings 20. The mixture may be further enriched by operating the wedge 52, which lifts the fulcrum arm 43 and raises the needle valve 12 to more than a normal extent so as to open the ports 10. As the speed of the engine increases and the degree of vacuum within the mixing chamber increases, the piston valve 18 responds to this influence and raises vertically from its nor-

mal lowered position within the mixing chamber. This causes a greater degree of opening of the air inlet conduit, a correspondingly increased opening of the needle valve and an increase in the area between the Venturi walls 19 of the piston and the rim 17 of the fuel valve, allowing for a greater inflow of the air and fuel in proportion to the increased fuel demands of the engine.

10 It will be noted that by the provisions of the openings 20 the piston valve can not operate as a positive "choke" for arresting air flow through the carburetor. As the piston valve continues to arise gradually and automatically within the mixing chamber in response to accelerated engine speed it has been found that increased fuel economy in the operation of the carburetor or engine can be obtained by allowing the needle valve to restrict the 20 inflow of the fuel but without curtailing the inflow of the air supply. This is accomplished by the provision of the adjustable cam 41, provided on the lever 43 which is directly connected with the needle valve 25 stem. It will be seen that as the piston valve 18 arises its movement is transferred to the bell crank lever 36 which, by means of the roller 39, controls the oscillation of the fulcrum arm 43 by engaging with the double 30 inclined cam surface 40 of the member 41. After the piston valve 18 has been elevated to a predetermined degree, controlled by setting the nut 45, the roller 39 engages with the apex portion of the cam member 41 and 35 passes to the other side of said cam member. Since the valve stem has been elevated to its maximum extent when the roller 39 is in contact with the apex portion of the cam surface 40, it follows that the movement of 40 the roller 39, past the apex results in the lowering of the needle valve and a corresponding reduction in the flow of the fuel through the diffusing valve. Thus, the carburetor is constructed to proportion automatically the relative quantities of air and 45 the liquid fuel so that a resultant mixture will be produced best suited to the requirements of an associated engine throughout its

entire work cycle. It will be observed that the operation of the carburetor is automatic 50 and requires no manual control other than that which may be imparted thereto by the wedge 52 when the engine is first started.

What is claimed is:

1. In a carburetor for an internal combustion engine, a casing, a fuel inlet nozzle within said casing and including an annular atomizing head, a stem for controlling fuel flow through said nozzle, a piston responsive to engine suction movably mounted 60 within said casing, an operating member movable in unison with said piston, a bell crank lever journaled exteriorly of said casing and connected with said operating member, a fulcrum lever for raising and lowering 65 said stem, said lever including a cam surface, and means provided in connection with said bell crank lever cooperative with said cam surface to rock said fulcrum arm and effect thereby changes in the operating positions of 70 said valve stem.

2. In a carburetor for an internal combustion engine, a casing, a liquid fuel nozzle in said casing, said nozzle including a reciprocating stem, a piston movably mounted within said casing and responsive to engine suction so as to occupy varying operating positions within said casing, a rod connected with said piston and extending exteriorly of 75 said casing, a fulcrum arm mounted on said casing and cooperative with the outer end of said valve stem to raise and lower said stem, the outer end of said arm being provided with an adjustable cam surface, and a bell crank lever pivoted upon said casing and having one end thereof connected with said rod and the other arm thereof arranged for wiping engagement with said cam surface, 80 said cam surface being formed so that upon the raising of said piston through a predetermined distance of travel corresponding movement will be imparted to said stem and upon further travel of said piston opposed movement will be imparted to said stem. 85

In testimony whereof I affix my signature.
JOHN W. COTTINGHAM.
